SEPARABLE ELECTRIC CONNECTION

Bert E. Kunkle, South Bend, Ind., assignor of
one-half to Florence E. Newhall, Chagrin Falls,
Ohio

Application March 1, 1935, Serial No. 8,918

2 Claims. (Cl. 173—330)

This invention relates to a separable electric connection suitable for household, office or similar uses, enabling the ready coupling of electric cords to wall receptacles, sockets, etc. The separable 5 plugs having two spaced prongs forming electric cord terminals now in common use have several disadvantages, among which may be mentioned the difficulty of inserting the prongs in positions where the socket is not readily visible; the liability of the prongs to become displaced when the 10 plug is detached, preventing their ready insertion in the openings, and the frequent breakage of the plug portion carrying the prongs.

It is an object of my invention to provide a terminal device for the cord and a complementary 15 terminal device for the fixed conductors which shall avoid the objections of the two prong connections and which, on the contrary, may be readily inserted without requiring the cord member to be in a certain position, and which shall 20 not be liable to distortion or breakage in use.

I accomplish the above object by providing a 25 cord plug of cylindrical form carrying a central contact and a concentric annular contact, and by providing a socket having contacts adapted to engage the two contacts of the plug irrespective of the axial position of the plug in the socket. This 30 enables the plug to be inserted in any position in a wall receptacle for instance, and there is no necessity for visual inspection of openings in the receptacle.

My plug has an annular insulating sleeve which carries an annular contact on its interior so that it is thoroughly protected. The socket member 35 has two concentric insulating sleeves with the contacts on the inside and outside of the inner sleeve. The result is that when the plug is inserted, the inwardly facing annular contact of the plug engages the outer socket contact and the 40 central contact of the plug engages the inner socket contact.

My invention adapts itself to a sturdy construction not liable to breakage or distortion and thoroughly insulated. The socket may, for 45 instance, be a fixed wall or floor receptacle or may be in the form of an adapter formed on one face to receive the plug and on the other with prongs or screw thread to engage present receptacles or lamp sockets, as desired.

Other characteristics of my separable electric 50 connection, and advantages resulting therefrom, will become apparent from a detailed description hereinafter given of preferred embodiments illustrated in the drawing hereof.

In the drawing, Fig. 1 is a side elevation, partly

broken away, of the complete device with the plug inserted in a wall or floor receptacle; Fig. 2 is a face view of the same, being a section through the contact carrying sleeve of the plug, as indicated by the line 2—2 in Fig. 1; Fig. 3 is a face 5 view of the socket member and a supporting bar therefor, as employed in a base or wall receptacle; Fig. 4 is a separated diametric sectional view of the plug and socket parts; Fig. 5 is a diametric section of an adapter having two prongs to enable the use of my plug with the present floor and wall receptacles; Fig. 6 is a diametric section of an adapter having a screw sleeve enabling the use of my plug with the present lamp socket.

As shown particularly in Fig. 4, the body of my 15 plug comprises a hollow cylindrical sleeve 10 having a head 11. This may be an integral member of insulating material, as hard rubber or "Bakelite". Rigidly mounted at the center of the head is a metallic post 12 forming the central contact, 20 and on the inner face of the sleeve 10 near its free end is a metallic sleeve 13 forming the annular contact. Each of these contacts is 25 metallically connected with binding screws on the outer face of the head 11. As shown, the central contact 12 has at its outer end a lateral bar 15 extending beneath the head of a screw 16 threaded in a nut 17 embedded in the head. Similarly, the metallic sleeve 13 has a longitudinal metallic extension 18, terminating in a bar 19 which extends 30 beneath the head of the binding screw 20, threaded in a nut 21 embedded in the head.

The construction described enables the ready attachment of the terminals of the cord to the terminals of the plug. The cord is illustrated 35 at A in Fig. 4, and its two conductors a, a', stripped of their insulation, are clamped by the screws 16 and 20 against the two contact bars 15 and 19.

The connections from the cord to the plug are 40 protected by a suitable insulating cap 30. This cap may be a cylindrical sleeve having a head 31 with a central opening for the passage of the cord, and may have on its inner annular face a screw 45 thread 32 engaging a thread 33 formed on the exterior of the sleeve 10. By unscrewing the cap from the sleeve into the position illustrated in Fig. 4, the cord conductors may be readily attached, after which the sleeve may be screwed down tight till the shoulder at the inner end of 50 the thread 32 abuts the end of the sleeve, and thereafter the two parts of the plug act as a unit.

It will be seen that by making the plug in two 55 insulating parts readily separable the cord may be very readily attached and may be suitably

knotted or bound, as indicated at **a2** in Fig. 4, so that any pull on the cord is taken by the head **31** of the cap and not by the binding screws. If desired, instead of screwing the sleeve **30** of the cap onto the sleeve **10** as shown, such sleeve **30** might be an integral portion of the sleeve **10** but in larger diameter, as indicated, and the head **31** might be removable from the sleeve **30**, being suitably attached in use by a screw thread or other means.

The socket member of my separable connection, illustrated in each of the figures, comprises two concentric spaced sleeves **40** and **41** of insulating material and a suitable head portion **42** connecting the sleeves at the inner end thereof. The annular space **43** between the two sleeves is of somewhat greater radial dimension than the thickness of the sleeve **10** with its contact **13**, while the bore of the sleeve **40** is larger than the exterior of the post **12**. Accordingly, the plug may be readily inserted into the socket.

The two contacts of the socket are carried on the inner and outer wall of the inner sleeve **40**; that is to say, there is a metallic spring contact **50** extending longitudinally along the inner wall of the sleeve **40**, and an outer contact **60**, which extends longitudinally along the outer side of the sleeve **40**. These contacts are electrically connected through the socket head with binding screws or other conductors, as hereinafter explained.

The contacts **50** and **60** are bowed inwardly and outwardly to some extent, as shown in Figs. 4, 5 and 6, to make a good spring contact with the post **12** and annular conductor **13** of the plug. It will be seen from Figs. 2 and 3 that these contacts **50** and **60** are in substantially the same radial plane,—that is, directly opposite each other on the same side of the axis of the plug—so that the lateral pressure of the contact **50** against the post **12** tends to pull the plug in the direction to make a tight connection between the sleeve **13** and the contact **60**. Similarly, the contact **60** tends to push the plug laterally in the opposite direction to cause a firm contact between the post **12** and the contact **50**. Accordingly, though the plug sleeve may be sufficiently smaller in external diameter than the internal diameter of the socket sleeve **41** to allow very easy insertion, there is still a tight contact when the plug is pushed into final position.

The sleeve **40** preferably terminates a short distance back of the plane defining the end of the sleeve **41**, so that there is a large circular shallow recess extending continuously across the inner face of the outer sleeve. When placing the plug in position it is only necessary that the sleeve **10** be located within this recess, after which the inward movement automatically makes a tight electric connection, irrespective of the angular position of the plug in the socket. The inner edge of the sleeve **41** is preferably rounded to aid in such ready insertion of the plug.

In the final position of the plug, the inner end of the sleeve **30** abuts the end **41** of the socket, as shown in Fig. 1, and the engagement of the contacts provides sufficient friction to prevent inadvertent displacement of the plug.

The description so far given of the socket applies to such socket whether embodied as a fixed receptacle or as an adapter suitable for separable attachment to a present wall receptacle or lamp socket, the only material difference being in the means for supporting the socket and

in the electric connections to the two contacts **50** and **60**.

In case of the fixed receptacle of Figs. 2, 3 and 4, the contact **50** turns outwardly in the form of a bar **51** and then is bent along the outer side **5** of the sleeve **41** at **52** while the contact **60** extends outwardly in the form of a bar **61**, and is then bent along the outer side of the sleeve at **62**. Binding screws **53** and **63** pass through the portions **52** and **62** of these contacts and are threaded in nuts embedded in the sleeve **41**, as indicated by the nut **64** in Fig. 4. The bar portions **51** and **61** of the contacts lying on the outer face of the head **42** of the socket may be protected by an insulating disc **70**, secured to the socket **15** by screws **71**. These same screws may secure a supporting bar **75** to the base of the socket.

The supporting bar **75** is shown in Fig. 1 as made of stirrup form to provide straight portions in a plane a short distance behind the plane of **20** the open end of the socket. These straight portions have slots **76** by which the bar may be attached to the fixed wall box **77** in the usual manner. The supporting bar **75** has threaded openings **78** for the reception of screws **79** holding in place a cover plate **80** which has a round opening through which the sleeve **41** slightly projects.

It will be noted from Fig. 3 that the supporting bar **75** lies at an oblique angle to the conducting bars **51** and **61**, and accordingly the binding screws **53** and **63** are out of the range both of the supporting bar and the walls of the box **77** parallel with the edges of that bar. The cavity of the box, therefore, need not be materially wider **35** than the external diameter of the socket.

To enable the socket to be used as an adapter in place of the present two-prong plug, I may embody it in the form shown in Fig. 5. Here the insulating member having the two sleeves **40** and **41** and head **42** is just the same as heretofore described, but the inner contact **50** terminates in a flat portion **55** on the outer face of the head **42**, while the outer contact **60** terminates in a flat portion **65** at the inner end of the annular space **43**. Suitable screws **90** and **91** connect these flat portions respectively with prongs **92** and **93** positioned in correspondence with the present two-prong plugs. This construction enables the socket member to be readily mounted on the exterior of the present installations in place of the present two-prong plug, and may be left in that position suitable for the reception of the cord plug **10**.

In Fig. 6, I have shown the same socket construction with sleeves **40**, **41** and a head **42** and contacts **50** and **60**, but the socket is embodied in an adapter suitable for mounting in an ordinary lamp socket; that is to say, there is an extension of the head **42** in the form of a boss **45** in which is mounted a central post **95** extending axially from a central contact **96** and at its inner end secured by a nut to the contact **50**, while on the outer side of the boss **45** is a screw threaded metallic sleeve **97**, the upper end of which is connected to an extension **98** of the external contact **60**. This device may be mounted in a lamp socket, in the same manner as an ordinary lamp, and is then in position to receive the plug **10** heretofore described.

It will be seen from the above description that the socket member of my separable connection without change in the body thereof and with only slight changes in the electric connections may be embodied as a fixed socket or as an adapter **75**

for different mountings. When in place, the socket provides a comparatively large available recess in which the inner end of the plug 10-30 may be positioned without the slightest difficulty and without visual observation, after which an inward movement of the plug establishes a firm electric and mechanical connection. All of the electric connections are thoroughly insulated when the plug is being installed, all metallic parts thereof become inaccessible within the socket before the plug establishes electric connection; when it is in place all parts are entirely housed in insulating materials.

I claim:

- 15 1. The combination of a socket member, comprising a comparatively small sleeve, a comparatively large concentric sleeve, and a connecting head, all of insulating material, bowed spring contacts with their extremities lying respectively 20 against the inner and outer sides of the smaller sleeve, said contacts being positioned opposite each other in a common radial plane on the same side of the sleeve axis and connected with conductors outside of the sleeves, and a plug 25 having a sleeve adapted to enter the space be-

tween the two sleeves of the socket and provided with a central contact adapted to engage the contact within the inner socket sleeve and an annular contact on the interior of the plug sleeve adapted to engage the contact on the outside of 5 the inner sleeve of the socket.

2. In a separable electric connection, the combination of a socket member having a pair of concentric insulating sleeves, terminals lying respectively against the inner and outer wall of 10 the inner sleeve and located directly opposite each other in a common radial plane with reference to the axis of the inner sleeve, and on the same side of said axis, at least one of them being in the form of a spring reacting on the sleeve in 15 a manner to exert pressure in a radial direction, and a contact plug having an insulation sleeve adapted to enter the space between the two sleeves of the socket member, said plug having a central metallic post adapted to engage the 20 inner contact in the socket and having an annular metallic member on the inner face of its sleeve adapted to engage the outer terminal of the socket.

BERT E. KUNKLE. 25
